UNITED STATES PATENT OFFICE.

JOSEPH PARIZEAU, OF ST. JEAN BAPTISTE, MONTREAL, QUEBEC, CANADA.

CARRIAGE-TOP.

SPECIFICATION forming part of Letters Patent No. 319,996, dated June 16, 1885.

Application filed May 4, 1885. (No model.)

To all whom it may concern:

Be it known that I, JOSEPH PARIZEAU, a citizen of the Dominion of Canada, residing at the town of St. Jean Baptiste, county of Hochelaga, in the district of Montreal and Province of Quebec, Canada, have invented certain new and useful Improvements in Carriage-Tops; and I do declare the following to be a full, clear, and exact description of the invention, which will enable others skilled in the art to which it appertains to make and use the same.

In the annexed drawings, which show the invention, and which also form a part of this specification, Figure 1 represents a perspective view of a carriage body and top; Fig. 2, an enlarged portion of Fig. 1, showing the corresponding part of the top turned down and with improvement applied to it; Fig. 3, the same enlarged portion of Fig. 1 as in Fig. 2, showing also the corresponding part of the top turned down and without improvement applied to it; and Fig. 4, a detail drawing showing the improvement alone.

My invention relates to carriage-tops, the object being to support the hind quarters, A, when the top is turned down, so that the said hind quarters, A, will take the position A' shown in drawings, Fig. 2, instead of the position A², Fig. 3, which would be the one taken if only fastened at C and D, and thus get soiled with mud, as it generally happens in that case. Sometimes the hind quarters, A, are brought close to the easy back E, and are supported in position A', Fig. 2, by tacking them to the said easy back E at E' and at both ends. This arrangement, however, not only spoils the easy back, but also the hind quarters, by tearing them when the least tension is brought to bear upon them.

As can be seen by drawings, I support the hind quarters, A, by means of the triangular

piece F, (the object of the invention,) and which is sewed, riveted, clinched, or in any other suitable way secured to them. This piece F is made of the same material as the hind quarters, A, or of any other suitable material. If the material employed should not have the necessary stiffness where attached to the hind quarters, A, a metal band, wire, or any other suitable stiffening material could be put on to give the sufficient stiffness to prevent the crisping of the hind quarters, A. The piece F is made so as to be attached to the easy back E at E', either by buttoning it on a stud, g, as shown in the drawings, or in any other suitable manner fastening it to the said easy back. In case where a stud, g, is used, the piece F is provided with a button-hole, a.

The reason for giving F the form shown is to keep the hind quarters, A, in good order by having them stretched their full width at all times. The advantages of this arrangement are, first, it keeps the hind quarters, A, from crisping; second, it does not spoil either the easy back or hind quarters; third, it can be removed at will; fourth, and above all, it keeps the hind quarters from hanging down, as shown at A', Fig. 2.

Having fully described my invention, what I claim, and desire to secure by Letters Patent, is—

In a carriage-top, the piece F, provided with the button-hole a, or any other suitable method of fastening, in combination with the hind quarters, A, stud g, and easy back E, all as above described, and for the purposes set forth.

In testimony whereof I affix my signature in presence of two witnesses.

JOSEPH PARIZEAU.

In presence of—

J. B. RESTHER,
D. A. MARCHAND.
